CLAIM

We claim the ornamental design for an artificial leaf antenna cover, as shown and described.

DESCRIPTION

FIG. 1 is a top plan view of an artificial leaf antenna cover showing our new design;

FIG. 2 is a bottom plan view thereof;

FIG. 3 is a side elevational view thereof, the opposite side being a mirror image;

FIG. 4 is a front elevational view thereof; and,

FIG. 5 is a rear elevational view thereof.
